(57) **CLAIM**

The ornamental design for a component for a perimeter barrier for a building structure, as shown and described.

DESCRIPTION

FIG. 1 is an isometric view of a component for a perimeter barrier for a building structure.

FIG. 2 is an end view thereof.

FIG. 3 is a front view thereof.

FIG. 4 is a front view thereof.

FIG. 5 is a rear view thereof.

FIG. 6 is a rear view thereof; and,

FIG. 7 is a perspective view of the component of FIG. 1 installed as part of the perimeter barrier of the building structure shown in broken lines.

The broken lines in the drawings illustrate the break lines of the component for a perimeter barrier for a building structure which form no part of the claimed design. Any portion of the component for a perimeter barrier for a building structure between the break lines also forms no part of the claimed design. The other broken lines in FIG. 7 illustrate environmental structure that also form no part of the claimed design.
